United States Patent Office

Des. 211,682
Patented July 16, 1968

211,682

CONTAINER FOR DAIRY PRODUCTS OR THE LIKE

Clara Virginia Eicholtz and Robert W. VanSickle, Midland, and Bertrand N. Trombley, Bloomfield Hills, Mich., assignors to The Dow Chemical Company, Midland, Mich., a corporation of Delaware

Filed Nov. 28, 1967, Ser. No. 9,564

Term of patent 14 years

(Cl. D9—219)

Fig. 2

Fig. 1

Fig. 3

Fig. 4

FIGURE 1 is an elevational view of a container for dairy products or the like showing our new design;

FIGURE 2 is a top view thereof;

FIGURE 3 is a bottom view thereof; and

FIGURE 4 is a fragmentary cross sectional view thereof, taken along the line 4—4 of FIGURE 2.

The sides of the container not shown are the same as the side illustrated in FIGURE 1.

We claim:

The ornamental design for a container for dairy products or the like, substantially as shown and described.
